UNITED STATES PATENT OFFICE.

SAMUEL GOLDSTEIN, OF BROOKLYN, NEW YORK.

CLAMP FOR CONCRETE-COLUMN FORMS.

1,370,888.

Specification of Letters Patent.

Patented Mar. 8, 1921.

Application filed June 9, 1920. Serial No. 387,537.

To all whom it may concern:

Be it known that I, SAMUEL GOLDSTEIN, a citizen of the United States, residing at 624 Howard avenue, Brooklyn, county of

5 Kings and State of New York, have invented certain new and useful Improvements in Clamps for Concrete-Column Forms, fully described and represented in the following specification and the accompanying drawings, forming a part of the same.

The present invention relates to a clamp for embracing the outer sides of a concrete mold, particularly for concrete.

Such molds are commonly formed of 15 planks which require to be held in a definite position to produce a molded body of the desired form and cross-section.

The invention is especially applicable to holding the plank in place for molding a 20 column of polygonal form, and the means described herein can be used for molding a column of four or more sides and of any diameter within certain limits.

The clamp is formed of clamping-bars 25 hinged together at one end and overlapped and crossed at corners intermediate to the pivoted ends; and the invention relates especially to the use of rigid angle-pieces for application to the clamping-bars outside of 30 their crossing-points.

These angle-pieces are constructed to lie upon the flat sides of the clamping-bars and are provided with flanges extending along the edges of the clamping-bars, and such 35 flanges are preferably provided with hook-pieces which project beneath the clamping-bars so as to wholly embrace the bars.

The two arms of each angle-piece are connected at their inner corner, and their 40 brace of two clamping-bars serves to hold the flat sides of the clamping-bars in contact with one another at their crossing-point.

A series of slots is formed lengthwise in the clamping-bars, and one or more slots in 45 each arm of the angle-piece adapted to receive a wedge which presses against the outer end of a slot in the clamping-bar and against the inner end of a slot in the angle-piece.

50 When the wedge is thus crowded into the slot it operates to draw the clamping-bar outwardly from the crossing-point, thus drawing the connected clamping-bar toward such crossing-point and crowding it 55 against one side of the mold.

Wedges are operated in both arms of the angle-piece simultaneously or successively and thus tighten the mold-planks upon two sides of the mold.

One clamping-bar is required for each 60 side of the mold, and with a four-sided mold two jointed pairs of the clamping-bars are required. In like manner, one-half as many pairs are employed as there are sides upon the mold. 65

The invention will be understood by reference to the annexed drawing, in which Figure 1 is a plan of the clamping device applied to a four-sided mold; Figs. 2 and 3 show the device applied respectively to 70 molds with six and eight sides. Fig. 4 is a plan of two clamping-bars joined together by a pivot; Fig. 5 is a plan of one angle-piece; Fig. 6 is a section on line 6-6 in Fig. 5; Fig. 7 is a section on line 7-7 in 75 Fig. 5; Fig. 8 is a side elevation of the clamping device with one side of the mold formed of four planks; Fig. 9 is a section on line 9-9 in Fig. 5; and Fig. 10 is a side-view of a wedge. Fig. 6 shows the clamp- 80 ing-bar also, with the wedge inserted in the slots of the angle-piece and clamping-bar, the wedge being shown in dotted lines.

Figs. 4, 5, 6, 7 and 9 are drawn upon a larger scale than the other figures. 85

Referring to Fig. 1, *a* represents the planks of a four-sided mold. *b* are the clamping-bars formed each with a series of slots *c* as shown in Fig. 4, hinged together at one end by pivot *b'*. Two pairs of the 90 clamping-bars are shown in Fig. 1 and two angle-pieces consisting of the arms *d* connected rigidly together and fitted to the flat sides of the clamping-bars outside of their crossing-point. 95

The arms of the angle-piece are not secured to the clamping-bars, but are provided each with a flange *f* or *f'* fitted to the outer edge of the clamping-bars outside of their crossing and such flanges are preferably provided each with a hook-piece *g* or *g'* extending beneath the clamping-bars and serving to hold the same in contact with the bars which it crosses adjacent to the corner of the angle-piece, and to guide the wedge 100 in a vertical line.

The hook-piece *g* forms, as shown in Fig. 6, a groove or channel *h* which is fitted to one of the clamping-bars, and as such clamping-bars cross one another they do 110

not lie in the same plane, and the channels for them in the respective arms of the angle-pieces are made on different planes.

One of the channels *h*, as shown at the 5 left-hand end of Fig. 6, is in a line with the plate of the angle-piece, but the channel *h'* in the other arm is below the level of the plate, as shown at the right-hand end of Fig. 7.

10 The arms of the angle-pieces are shown provided with slots *e* and *e'* which, in practice, are sloped at one end to fit the wedge *i*, and are made longer than the slots *c* in the clamping-bars to clear the vertical side 15 of the slot from the wedge. The slots *e* and *e'* are extended through the hook-piece *g* in their passage through the slot of the clamping-bars which lie in the channel *h*.

When the angle-pieces are applied to the 20 bars at their crossing, as shown in Fig. 1, the ends of the bars extend outside of their crossing and the flanges *f* and *f'* of the two angle-pieces are fitted to the outer edges of such clamping-bars.

25 The slot *e* in the angle-piece is made longer than the slots *c* so as to permit the point of the wedge to enter one or another of the adjacent slots *c* through the slot *e*, as shown in Fig. 6. When the wedge is 30 thus adjusted and driven into the slots it draws the end of the clamping-bar outwardly from its crossing, the flange *f* upon the other arm of the angle-piece sustaining the strain of thus crowding the clamping-bar and tightening the planks along which it lies.

The range of the draft or pull effected by 40 the complete movement of the wedge may be in practice made about one inch, and when the wedge has effected such specific movement as shown in Fig. 6, the adjacent slot *e* would be accessible to the long slot *e* and the tightening movement can be continued by inserting another wedge in such 45 other slot, continuing the movement as far as required.

Either of the slots *e*, *e'* can be used in each angle-piece, which appears to be in the most favorable position to insert the wedge. 50 The wedges are left in the slots when the mold is fully tightened, retaining the clamping-bars in their adjusted position until the mold is dismantled.

The operation is precisely the same with 55 a mold of six or eight sides, but the angle-piece is made with an angle of 120 degrees between its arms for a six-sided mold, and 135 degrees for the eight-sided mold, instead of 90 degrees, as shown in Fig. 1 for the 60 four-sided mold.

To show the arrangement of the clamping-bars more clearly in Figs. 2 and 3, only one of the angle-arms is shown applied to one corner of the mold, but it will be understood 65 that they are applied in practice to all the

alternate corners the same as in the four-sided mold, the pivots of the clamping-bars lying over the intermediate corners of the mold.

The construction of the angle-piece with 70 arms attached rigidly together enables each arm to support the other; that is, to resist the thrust of the wedge upon the arm and thus enable it to directly pull or draw upon the clamping-bar. 75

To enable the angle-arms to sustain one another in tightening up the mold, it is desirable that wedges should be inserted through the slots *e* or *e'* of each angle-arm, thus holding each arm fixed upon its 80 clamping-bar while the wedge is being tightened in the other arm.

The two arms of the angle-piece may, to facilitate shipping, be made separate, and engaged together in any desired manner to 85 connect them rigidly when in operation.

I am aware that clamping-bars perforated with bolt-holes are old, and that angle-pieces have been used in connection with such angle-bars to support the thrust of a 90 cam, but the cam is not used in such case as a locking-member, and such bars can only be secured together at certain fixed distances at which the bolt-holes are located; whereas the employment of wedges in my construction 95 permits the clamping-bars to be tightened up to any amount greater or less and held or locked rigidly in such tightened position by the same means which tighten them namely, the wedge inserted in the slot. 100

In my construction the wedge performs a twofold function, as it is the tightening agent as well as the locking agent for the clamps when tightened.

Having thus set forth the nature of the invention what is claimed herein is:

1. A clamp for concrete column forms having clamping-bars overlapped and crossed at a corner of a mold, and angle-pieces having arms connected together in different planes and fitted to the sides of the crossed clamping-bars, the said bars and the arms of the angle-pieces having slots with wedges fitted thereto and operating respectively to press the said arms against the adjacent sides of the mold. 110

2. A clamp for concrete column forms comprising clamping-bars in pairs pivoted together at one end, the bars of the pairs crossed at corners intermediate to the pivots 120 and angle-pieces applied to the clamping-bars outside of their crossings, such bars and angle-pieces being provided with slots and wedges to crowd the bars at their crossing against the mold-planks. 125

3. A clamp for concrete column forms comprising at least two pairs of clamping-bars each with a series of uniformly spaced short slots and the bars overlapped and crossed at corners intermediate to their piv- 130

ots, and angle-pieces having flanges fitted to the clamping-bars outside of their crossings, and the arms of each angle-piece having long slots to receive a wedge adapted to coöperate successively with the short slots in the 5 clamping-bars.

4. A clamp for concrete column forms comprising at least four clamping-bars pivoted in pairs and formed each with a series 10 of uniformly spaced short slots, and the bars overlapped and crossed at corners intermediate to their pivots, and angle-pieces having flanges fitted to such clamping-bars outside of their crossing and having long slots to receive a wedge adapted to coöperate with the short slot in the clamping-bars.

5. A clamp for concrete column forms comprising at least two pairs of clamping-bars each pair having its bars pivoted together at one end and formed with a series 20 of uniformly spaced short slots and overlapped at corners intermediate to the pivots, and angle-pieces with flanges fitted to such clamping-bars outside of their crossing, and 25 having long slots adapted to admit a wedge in connection with the short slots in the clamping-bars, such wedge operating to crowd the angle-piece and the clamping-bar against the planks of the mold.

30 6. A clamp for concrete column forms comprising at least two pairs of clamping-bars each pair having its bars pivoted together at one end and formed with a series of short slots and overlapped and crossed 35 at corners intermediate to the pivots, and angle-pieces having slots to coöperate with those in the clamping-bars, and flanges fitted to such clamping-bars outside of their crossing, each flange having a hook-plate to 40 embrace the under side of the clamping-bars and hold it movably in place when fitted thereon.

7. A clamp for concrete column forms comprising at least two pairs of clamping-bars each pair having its bars pivoted together at one end and formed with a series 45 of uniformly spaced slots, and overlapped

and crossed at corners intermediate to the pivots, angle-pieces having slots to coöperate with those in the clamping-bars, and 50 having flanges fitted to the outer edges of such clamping-bars at their crossing, and two slots longer than the slots in the clamping-bars, adapted to admit a wedge in one of the longer slots and one of the short slots 55 during a specific clamping movement of the clamping-bars, and to thereafter engage the other long slot with one of the short slots in the clamping-bars.

8. A clamp for concrete column forms 60 comprising at least two pairs of clamping-bars each pair having its bars pivoted together at one end and formed with a series of short slots and overlapped and crossed at corners intermediate to the pivots, and 65 angle-pieces having two arms each formed with flanges fitted to such clamping-bars outside of their crossing and both arms having a series of slots, and wedges fitted through slots in both of the said arms and 70 engaging slots in the corresponding clamping-bars and operating when tightened in the slots to crowd both clamping-bars against the planks of the mold.

9. A clamp for concrete column forms 75 having pairs of clamping-bars each pair having its bars pivoted together at one end and overlapped and crossed at corners intermediate to the pivots, angle-pieces having arms connected together in two planes and fitted 80 to rest upon the sides of the crossed clamping-bars, the said bars and the arms of the angle-pieces having slots adapted to admit wedges and having flanges fitted to such clamping-bars outside of their crossing and 85 each flange having a hook-plate to embrace the under side of the clamping-bar and operating to hold the sides of the crossed clamping-bars in contact with one another intermediate to the pivoted end.

90 In testimony whereof I have hereunto set my hand.

SAMUEL GOLDSTEIN.
